UNITED STATES PATENT OFFICE.

WILLARD A. HANCE, OF FREEPORT, ILLINOIS, ASSIGNOR TO STOVER MANUFACTURING COMPANY, OF FREEPORT, ILLINOIS, A CORPORATION OF ILLINOIS.

GRINDING-BUR.

1,185,901.

Specification of Letters Patent.

Patented June 6, 1916.

Application filed January 29, 1916. Serial No. 75,151.

To all whom it may concern:

Be it known that I, WILLARD A. HANCE, citizen of the United States, residing at Freeport, in the county of Stephenson and 5 State of Illinois, have invented certain new and useful Improvements in Grinding-Burs, of which the following is a specification, reference being had therein to the accompanying drawing.

10 The object of this invention is to provide grinding burs which will lessen the consumption of power and increase the output without increasing initial cost nor sacrificing durability.

15 It is well understood that grinding burs of the common metal type are not readily made to run precisely in a given path and that the slightest deviation causes one bur to cut its companion. It is also common to 20 provide means for retarding the discharge from the burs. To prevent initial injury by the burs and to retard delivery are results often secured by closing the grooves of the burs at the margins of the latter by integral 25 metal forming a smooth faced ring to meet the smooth surface of the companion bur and prevent contact of the grinding teeth. This expedient is effectual, but with certain materials it undesirably reduces the output 30 and increases the power used in running the mill. I have found that by closing in the way suggested the outer ends of some of the grooves, on all sides of the axis, and leaving intermediate grooves open, we have all the 35 advantages, and none of the disadvantages of the continuous ring. In grinding oats, for example, the gain is very great.

For illustration annular disk burs are shown although conical burs may be used.

40 In the drawings, Figure 1 is a plan view showing one working face of an annular bur having alternate grooves outwardly closed by integral metal which can be considered as part of a broken marginal ring.

45 Fig. 2 is an edge view of a portion of two coacting burs of similar construction. Fig. 3 is a section on the line 3—3, Fig. 2. Fig. 4 shows a segment of a disk bur in which every third groove is closed at the bur's periphery. Fig. 5 illustrates two consecutive closed grooves alternating with a single open groove.

In Figs. 1 and 2, A, A' designate the bodies of two coacting burs of annular disk form. Each has the usual general arrange-

ment of tangential ribs and each has its inner annular portion beveled from the working face toward the inner margin of the ring, and has at regular intervals a rib extended inward to said margin to form a 60 large feeding and breaking rib B the edge of which recedes but slightly from the working plane. The intermediate ribs C do not extend to that inner margin, and on the non-beveled portion of the ring have their edges 65 substantially in that plane. Alternate grooves D between the ribs are outwardly closed by integral metal portions E which may be considered as parts left by cutting away intervening portions of the old marginal ring, since all are of uniform height and have their working faces approximately in the plane of the working edges of the ribs. Obviously, rocking of the burs relatively, 70 will bring the smooth plane faces of the portions E of the two plates into contact and they will slip easily upon each other while preventing mutual injury of the sets of teeth on the two plates quite as effectually as the old continuous rings of which these may be 75 considered as remaining segments. At the same time material between the rings escapes from alternate grooves and is retained in intermediate grooves. It is found that 80 practically material does not fill and remain 85 in the closed grooves while passing rapidly out of the open grooves, but that material is carried from groove to groove, material which enters the inner end of a particular groove, open or closed, passes from groove 90 to groove owing to the rotation, and is delivered from a groove at some distance from the groove which it first entered. The material is therefore of practically uniform 95 fineness when delivered, and because the plates may run very close together, and yet deliver rapidly it is always finely ground. It is not indispensable that single closed and open grooves alternate. Two open grooves 100 may alternate with single closed grooves as in Fig. 4 or with single open grooves as in Fig. 5. Other similar changes may be made, one or more closed grooves alternating with one or more open grooves. Nor is exact uniformity, in passing around the disk, indispensable, the essential feature being that some grooves are open and some closed in 105 every third at least of the circle.

What I claim is:

1. A grinding bur having the body of its 110

working face provided with grooves separated by narrow grinding ribs, some of the grooves at short distances from each other being closed at their outer ends only by integral metal forming peripheral bearing surfaces substantially in the plane of the working edges of the ribs while intermediate grooves are open at their outer ends.

2. A grinding bur having the annular peripheral portion of its working face provided with thin tangential grinding ribs many of which extend, distinct from their companions, to the periphery of the bur while intermediate ribs are integrally connected at their outer ends by segments having substantially the same height as the ribs.

3. A grinding bur having in the annular outer part of its working face tangential

grooves separated only by thin grinding ribs, said grooves at short intervals around the periphery of the bur being closed at their outer ends only by integral metal forming bearing surfaces to prevent mutual injury of the ribs of co-acting burs and obstructing the outward flow of material in the corresponding grooves causing it to pass over from groove to groove increasing the fineness of the product without materially increasing friction.

In testimony whereof I affix my signature in presence of two witnesses.

WILLARD A. HANCE.
